United States Patent Office

Des. 193,911
Patented Oct. 23, 1962

193,911

BOTTLE OR SIMILAR ARTICLE

Alfred D. Sterges, Los Angeles, Calif., assignor to Purex Corporation, Ltd., South Gate, Calif., a corporation of California

Filed Apr. 6, 1962, Ser. No. 69,616

Term of patent 14 years

(Cl. D58—6)

FIG. 1.

FIG. 2.

FIG. 3.

FIG. 4.

FIG. 1 is a side elevational view of a bottle embodying my new design, the side of the bottle not shown being the same as the side shown;

FIG. 2 is an end elevational view thereof, the end not shown being substantially the same as the end shown;

FIG. 3 is a top plan view thereof;

FIG. 4 is a bottom plan view thereof.

I claim:

The ornamental design for a bottle or similar article, substantially as shown and described.
